(57) **CLAIM**

The ornamental design for a hub of vehicle wheel as shown and described.

DESCRIPTION

FIG. 1 is a first perspective view of a hub of vehicle wheel showing my new design;

FIG. 2 is a second perspective view thereof;

FIG. 3 is a front view thereof; and,

FIG. 4 is a cross-sectional view taken along line 4-4 in FIG. 3 thereof.

The broken lines depict portions of the hub of vehicle wheel in which the design is embodied that are not considered part of the claimed design.

The dot-dash lines show a boundary between the claimed design and unclaimed portions.
